UNITED STATES PATENT OFFICE

MARIAN B. HEATH, OF MEADVILLE, PENNSYLVANIA

DESIGN FOR A BOX OR SIMILAR RECEPTACLE

Application filed February 23, 1932. Serial No. 42,962. Term of patent 7 years.

To all whom it may concern:

Be it known that I, MARIAN B. HEATH, a citizen of the United States, residing at Meadville, in the county of Crawford, and State of Pennsylvania, have invented a new, original, and ornamental Design for a Box or Similar Receptacle, of which the following is a specification, reference being had to the accompanying drawing, showing my new design, wherein:

The figure is a perspective view of a receptacle embodying my new design.

I claim:

The ornamental design for a box, or similar receptacle, as shown.

MARIAN B. HEATH.
